UNITED STATES PATENT OFFICE

131,626

DESIGN FOR A GAUGE

Sheldon B. Ellwood, Studio City, and Ralph E. Pettit, Jr., Hollywood, Calif.

Application February 10, 1941, Serial No. 98,877

Term of patent 7 years

To all whom it may concern:

Be it known that we, Sheldon B. Ellwood and Ralph E. Pettit, Jr., citizens of the United States, residing, respectively, at Studio City and Hollywood, both in the county of Los Angeles, and State of California, have invented a new, original, and ornamental Design for Gauges, of which the following is a specification, reference being had to the accompanying drawing, forming part thereof.

Figure 1 is an elevational view of a gauge, showing our new design, and

Figure 2 is a top plan view thereof.

We claim:

The ornamental design for a gauge, as shown.

SHELDON B. ELLWOOD.
